J. M. CALLAHAN,
ADJUSTABLE ARCH SUPPORT FOR SHOES.
APPLICATION FILED JULY 20, 1915.

1,187,255.

Patented June 13, 1916.

UNITED STATES PATENT OFFICE.

JAMES MARION CALLAHAN, OF WASHINGTON, DISTRICT OF COLUMBIA.

ADJUSTABLE ARCH-SUPPORT FOR SHOES.

1,187,255.

Specification of Letters Patent. Patented June 13, 1916.

Application filed July 20, 1915. Serial No. 40,868.

To all whom it may concern:

Be it known that I, JAMES M. CALLAHAN, a citizen of the United States, residing at Washington, in the District of Columbia, have invented a new and useful Adjustable Arch-Support for Shoes; and I do hereby declare the following to be a full, clear, and exact description of the invention, such as will enable others skilled in the art to which it appertains to make and use the same.

Owing to excessive walking and standing, particularly upon hard surfaces, a great many persons, distort, stretch or break, or disjoint the muscles or ligaments of the instep, thereby causing flat feet, fallen or broken arches, which are more or less inconvenient, and in great many cases extremely painful, thereby quickly producing a tired feeling and preventing any great amount of walking.

Therefore, an object of this invention (which relates to a new and useful adjustable arch support to be worn upon the interior of the shoe adjacent the arch or instep) is to provide an improved device of this design, for strengthening, reinforcing, and restoring fallen or broken or wrenched arch or instep to its normal condition, so that a person can walk without inconvenience and excruciating pain.

Another object of the invention is to provide a plurality of pads of different thicknesses, and of which only one is illustrated, so that an arch may gradually build up, strengthen, or reinforce.

The invention further aims to provide an adjustable pad, adjustable intermediate between the lowermost reinforcing metal plate of the support and a fiber strip, so that the pad may be arranged to conveniently conform to the curvature of the arch, for strengthening and reinforcing the same.

Another object of the invention is to construct the pad or pads from rubber, felt, or any other suitable material, having suitable adjustable fastening means to the lowermost reinforcing metal plate, in order to be adjusted as required.

Another object of the invention is the provision of a fiber piece above the pad (which is removable, renewable, or replaceable, and when removed the space between the plate and the upper piece may be cleaned) and riveted to the lowermost reinforcing metal strip, so that its forward end may be raised so that the pad can be removed, the upper

fiber piece being so constructed toward its rear as to contact with the rear heel portion of the shoe to form an abutment, to limit the support in its backward movement and to prevent creeping thereof.

Another object of the invention is to provide a lowermost metal supporting plate of the arch with a reinforcing groove or rib, for stiffening and bracing the plate. However, this rib or groove may be dispensed with if desired.

In practical fields the details of construction may necessitate alterations, falling within the scope of what is claimed.

The invention comprises further features and combination of parts, as hereinafter set forth, shown in the drawings and claimed.

In the drawings:—Figure 1 is a view in perspective of the improved arch support arranged in the shoe, which is shown in dotted lines, and illustrating the upper fiber piece as lifted, and the pad ready to be inserted. Fig. 2 is a sectional view through a portion of the shoe, showing the arch support as applied. Fig. 3 is a sectional view on line 3—3 of Fig. 2. Fig. 4 is an enlarged detail sectional view showing the fastening means of the pad with the lowermost strengthening or reinforcing plate. Fig. 5 is an enlarged bottom plan view of the under face of the lowermost metallic reinforcing plate, showing parts broken and illustrating the pad, and showing the fastening means on an enlarged scale.

Referring more especially to the drawings, 1 designates the instep or arch portion of a portion of the shoe 2, whereas 3 denotes the lowermost reinforcing metal plate, which is designed to fit within the shoe, and to extend substantially the full length of the arch or instep of the shoe and protrude partially upon a portion of the ball of the sole of the shoe, thereby preventing excessive distortion or sagging of the instep of the shoe. The thickness of the plate 3 gradually tapers off at 4 toward its forward portion, and tapers off at 5 toward its rear portion. The rear tapered portion of the plate 3 may terminate any distance beyond the point of the instep 6, as indicated in Fig. 2, but not to extend completely at the rear of the heel of the shoe. This plate 3, with the exception of the groove or rib 7 is substantially flat toward its outer edge 8, and which rib or groove may be employed or dispensed with, as desired. The side of the

plate 3 opposite the side portion 7 is curved outwardly and upwardly as shown at 8 and gradually tapers off as shown at 9, thereby forming a curved flange 10, which reinforces and strengthens the inner curve of the arch or instep of the wearer's foot. The plate 3 is designed to be substantially of the shape shown, but it is to be remembered that the shape may be varied as desired, to suit the various makes and contours of shoes. The flange or lip 10 gradually tapers or merges or blends off and into the forward portion of said plate 3, as shown at 11, whereas the rear portion of the flange 15 or lip 10 gradually merges, blends or tapers off at 12 toward the rear of the plate, so as to conform to the inner curvature or contour of the instep or arch of the wearer's foot. Designed to be riveted at 13 and 14 adjacent the rear of the plate is a leather or other fiber piece 15 (which may be termed, if desired, a substantially half length insole) and this leather or fiber piece 15 adjacent its inner side edge is provided with an extension flange or lip 16, which substantially or partially conforms to the contour of the flange or lip 10. This flange or lip 16 also merges or tapers off or blends into the piece toward its forward and rear portion, somewhat correspondingly to the gradual tapering or blending of the flange or lip 10. This leather or fiber piece 15 may be riveted to the plate 3 at any suitable place, otherwise than shown, according to the makes and contour of different shoes. The heel portion 17 of the leather or fiber piece may be somewhat dished, as shown, so as to conform to the under curvature of the heel of the wearer. The heel portion 17 of the fiber piece 15 is somewhat thicker as shown, than the forward part thereof, but which thickness may be increased or decreased if desired, or may be substantially the same thickness as the forward portion 45 of the piece. However, the extremity 18 of the heel portion 17 of the piece 15 is designed to be blunt, and may be substantially the same thickness as shown at 17, which in combination with the necessary thickness 50 affords sufficient stiffness, whereby the extremity 18 forms an abutment against the heel portion of the upper of the shoe as at 19, to prevent the leather or fiber piece and the metal plate 3 (which are riveted together) from creeping rearwardly. The forward portion of the leather or fiber piece gradually tapers off as shown at 20, and is designed to overlie or overlap the forward tapered part 4 of the metal plate 3, so that 55 that portion of the bottom of the wearer's foot substantially intermediate the ball thereof and the arch will contact with a smooth and even surface, designed to be employed in connection with and intermediate the leather or fiber piece and the plate 3, 60 is a padding 21, which is designed to be constructed of rubber, felt or other suitable material. It is to be observed that the padding 21 gradually tapers off toward the rear and forwardly, as shown at 22 and 23, in order to neatly fit between the plate 3 and the leather or fiber piece 15, in such wise as to prevent bulges or unevennesses in the leather or fiber piece, thereby affording a smooth surface with which the wearer's foot 65 is designed to contact. The padding 21 slightly tapers toward its outer edge 24, whereas the opposite or inner portion of the padding is constructed with an upwardly and outwardly curved flange 25 tapering off as shown at 26, and designed to fit between and conform with the flanges or lips 10 and 16 of the plate 3 and the leather or fiber piece 15. 70 In using this improved reinforcing arch support, one after another of the plurality of paddings is designed to be used, thereby building up the arch or instep of the wearer's foot, until it resumes its normal shape, and after constant wearing of the requisite thickness of padding, the arch or instep of the wearer's foot will maintain its normal condition and curvature. That portion 27 of the padding adjacent where it merges into the lip or flange 25 is of greater thickness than that portion adjacent its outer edge 24. The padding 21, when made of rubber, may be made in any suitable manner, either by molding, vulcanizing or otherwise. However, when constructed, the same 75 is provided with a plurality of headed studs 28, the disk plates 29 of which may be embedded in the rubber padding, in any suitable manner, for instance, by being molded within the padding when the padding is 80 molded, or vulcanized within the padding. Furthermore, the studs may be connected to the padding at any suitable location, otherwise than shown, and the heads 30 of the studs are substantially elongated and rectangular in shape, but which shape may be varied. The head of one of the studs assumes a position at a slight angle to the opposite stud, owing to the same being so arranged or vulcanized in the pad, for the purpose to be hereinafter stated. The plate 3 is provided with a plurality of slots or openings arranged in rows as shown. The slots 32 of one row are disposed at right angles to the slots 33 of the opposite row, and both rows of 85 slots may be increased or decreased in number, or disposed in any other suitable manner than that shown, provided one row is substantially opposite to the other, or the equivalent of such arrangement. Both 90 rows of slots upon the under face of the plate 3 are provided with adjoining circular counter-bores 34 and 35, so as to receive the heads 30 of the studs when the pad is 95 arranged in place. The shanks of the studs 100

110

115

120

125

130

are cylindrical, and when the pad is to be arranged in place (which is accomplished before inserting the arch support in the shoe), the head 30 of the stud adjacent the 5 outer side edge 24 of the pad is passed through one of the slots 32 (the pad having been first turned, so that the elongated head registers with one of the slots 32) after which the pad is turned or adjusted to its 10 proper position with the lip or flange 25 in contact with the lip or flange 10, causing the head 30 of the stud to engage the counter-bore 34 of the slot 32. The pad adjacent the flange or lip 25 is then distorted or 15 twisted sufficiently, to cause the angularly disposed head of the other stud (which is adjacent the lip or flange 25) to snap into one of the slots 33, so that the elongated head of said stud will partially engage the 20 counterbore adjacent or adjoining the slot 33, thereby locking the pad to the plate 3 and between the plate and the piece 15. To cause the head of the stud to more readily snap through the slot 33, the slot adjacent 25 the upper face of said plate 3 is suitably curved or beveled off, as shown at 36 particularly in Fig. 4, which will necessitate requisite pressure to cause the head of the stud to wedge through the slot. If necessary, 30 after the head has thoroughly passed through the slot 33, a pair of pliers or other suitable tool (not shown) may be used for grasping the head, in order to impart a partial turn to the head of the stud, in fact, turn the stud, 35 to cause the head to further engage the counter-bore.

From the foregoing it is to be observed that there has been devised an improved arch support, adapted to be worn upon the 40 interior of the shoe, and which support is simple and efficient in construction, and has been found effective and practical for reinforcing, strengthening and restoring fallen, broken, wrenching or otherwise weakened arches or insteps of persons' feet.

The plate 29 of one of the headed studs is provided with ribs 50 upon one of its surfaces to prevent the plate and the stud from turning. Similar ribs may be provided 50 upon the plate 29 of the other stud if so desired, and if necessary the studs can be turned, even though the ribs are used, by employing a pair of pliers (not shown) or other suitable tool. The ribs are provided 55 for the purpose of preventing the plates and the studs from turning accidentally, and if desired the ribs may be dispensed with. If one of the studs is turned, that is, the one having the ribs on its plate 29, by means of 60 pliers or other tools, it will not hinder the ribs from holding the plate from accidental turning or displacement.

Very often the arched metallic plate in arch supports of this nature engages flush 65 through the entire length of the shoe, and if

the arch support is built to raise the arch or the instep of the foot at certain heights, and if the fasteners between the cushioning pad should protrude below the under face of the main plate of the support, said fasteners 70 would tend to raise the arch support higher than is necessary. Furthermore, if the fasteners protruded below the under face of the main plate, the fasteners would tend to injure or mar the upper surface of the arch 75 of the shoe. Therefore, a particular advantage in countersinking the heads of the fasteners of the cushioning pad in the under surface of the main plate, is to avoid raising the arch support higher than is necessary, 80 and to prevent the fasteners from injuring the upper surface of the arch of the shoe. By varying the thickness of the rear portion of the insole beyond the rear ends of 85 said plates and abutting the rear edge of the insole against the heel of the shoe, the support will raise and accommodate the heel of the foot in accordance with the height of the arch of the foot. In other words, it is the aim of the invention to provide the 90 insole at its rear with varying thicknesses, so that the arch support, and the varying thicknesses of the insole, will raise the arch and the heel of the foot correspondingly.

The invention having been set forth, what 95 is claimed as new and useful is:—

1. An arch support, comprising a reinforcing metallic plate designed to expand the arch of a shoe on the interior thereof and provided with two rows of slots, the slots 100 of one row extending at right angles to the slots of the other row and being substantially oppositely disposed, said slots having adjoining counter-bores adjacent the under face of said plate, a fiber piece having one 105 end portion secured to said plate and extending rearwardly and forwardly and overlying both ends of the plate, and a one piece cushioning pad interposed between the fiber piece and the plate and having a pair of 110 headed studs embedded therein, said studs adapted to enter the openings, whereby their heads are adapted to engage the counter-bores, said heads being of thicknesses substantially equal to the counterbores so that 115 the heads are flush with the under surface of the plate, the head of one of the studs being at a slight angle to the head of the other stud, thereby requiring an angularly disposed head to be snapped into its opening subsequently to the insertion of the other lug into its opening.

2. An arch support, comprising a reinforcing metallic plate designed to expand the arch of a shoe on the interior thereof 120 and provided with two rows of slots, the slots of one row extending at right angles to the slots of the other row and being substantially oppositely disposed, said slots having adjoining counter-bores adjacent the under 125

- face of said plate, a fiber piece having one end portion secured to said plate and extending rearwardly and forwardly and overlying both ends of the plate, and a one piece 5 cushioning pad interposed between the fiber piece and the plate and having a pair of headed studs embedded therein, the heads of the studs being elongated, and said studs adapted to enter the slots, whereby their 10 heads are adapted to engage the counterbores, said heads being of thicknesses substantially equal to the counterbores so that the heads are flush with the under surface of the plate, the head of one stud being at a 15 slight angle to the head of the other stud, thereby requiring the angularly disposed head to be snapped into its slot subsequently to the insertion of the other lug into its slot, the slot that receives the angularly 20 disposed head having curved walls adjacent the upper surface of the plate to permit the angularly disposed head to more readily snap into the slot.
3. An arch support comprising in combination with a metallic plate adapted to expand the arch of the shoe on the interior thereof, a one piece cushioning pad having adjustable fastening connections with said plate adjacent the arch of the shoe, and a 25 fiber piece having one end secured near to the rear end of said plate and extending over the pad and having a rear heel engaging thickened and stiffened portion provided with a blunt edge, constituting abutting means at 30 the heel portion of the shoe to prevent creeping of the support rearwardly and preventing the rear terminal of the piece from creeping upwardly.
4. An arch support comprising a main 40 plate, having counterbored openings, an insole or covering having one of its end portions secured to one end of said plate, with its other end free and disconnected, and a cushioning pad having fasteners embedded 45 therein, said fasteners being provided with heads substantially equal to and engaging the full depths of said counterbored parts of said openings of the main plate.
5. An arch support comprising a main 50 plate, an insole or covering secured to one end of said plate, said plate having counterbored openings therein, and a cushioning pad insertible between the insole and said plate and having fasteners protruding 55 through said openings, said fasteners having heads substantially equal to and being embedded in the counterbored parts of said openings.
6. An arch support comprising a main 60 plate, an insole or covering secured to one end of said plate, said plate in its arch por-
- tion having opposite rows of openings, which are provided with counterbores adjacent the under surface of the plate, and a cushioning pad insertible between the insole 65 and said plate and having fasteners protruding through said openings, said fasteners having heads engaging the counterbores of said openings, said heads being flush with the under surface of said main plate. 70
7. An arch support comprising a main plate, an insole or covering secured to one end of said plate and having its other end free and disconnected, said plate in its arch portion having opposite rows of openings, 75 which are provided with counterbores in the under surface of the plate, and a cushioning pad insertible between the insole and said plate and having fasteners embedded therein and designed to protrude through said openings, said fasteners having heads engaging the counterbores of said openings, said heads being flush with the under surface of said main plate. 80
8. An arch support comprising a main 85 plate, an insole or covering secured to one end of said plate and having its rear portion extending beyond the plate varying in thickness toward the rear and abutting the heel of the shoe, the other end of said insole covering being free and disconnected, said plate in its arch portion having opposite rows of 90 openings, which are provided with counterbores in the under surface of the plate, and a cushioning pad insertible between the insole 95 and said plate and having fasteners, one adjacent each side of the pad, one of said fasteners designed to protrude through one of the openings of one row, subsequently turning the pad and passing the fastener at the 100 other side through the opening of the opposite row, said fasteners having heads engaging the counterbores of said openings.
9. An arch support comprising a main 105 plate, an insole secured to one end of said plate and having its rear portion extending beyond the plate and gradually varying in thickness and abutting the heel of the shoe, said plate having openings, a cushioning pad insertible between the insole and said 110 plate and having fasteners adjustably cooperating and protruding through said openings, said fasteners having heads countersunk in the openings and flush with the under face of said plate. 115
